[57] CLAIM

The ornamental design for a tips jar, as shown and described.

DESCRIPTION

FIG. 1 is a side perspective view of a tips jar showing my new design;

FIG. 2 is a side elevation thereof;

FIG. 3 is a top plan view thereof;

FIG. 4 is a bottom plan view thereof;

FIG. 5 is an exploded side elevation view; and,

FIG. 6 is a side elevation of a second embodiment of a tips jar showing my new design, the only difference being the transparent base.
